Application September 18, 1945, Serial No. 617,134

11 Claims. (Cl. 178—44)

1

The present invention relates to electrical energy, and more particularly to the transmission of such energy from one place to another by means of hollow pipes or the like. To a greater degree of particularity, the invention is concerned with devices for eliminating from a hollow wave guide one mode of transmission that may be undesirable while simultaneously permitting passage of a desired mode.

The subject matter of this invention is disclosed in the copending application of Shepard Roberts, S. N. 510,990, filed November 19, 1943, Patent No. 2,513,205, issued June 27, 1950, and in applicant's copending application, Serial No. 610,350, filed August 11, 1945, now Patent No. 2,584,399, issued February 5, 1952, wherein are described rotatable joints for wave guides. Advantage is therein taken of the fact that in a cylindrical wave guide carrying energy in a mode of axial symmetry, such as the TM_{01} or the TE_{01} mode, the wave guide may be made of two coaxial abutting sections and one section rotated on the common axis with respect to the other without disturbing the passage of the energy.

It should be noted that the terminology by which modes of oscillation of electrical energy in wave guides may be designated is of two sorts. A wave designated as TM_{01} may also, by another system be called E_{01} , or in a cylindrical wave guide simply E_0 , while a wave designated as TE_{11} may be called, in the other system, H_{11} , or in a cylindrical wave guide simply H_1 . In the present application, the system in which the mode is designated by the name of the component lying wholly transverse to the axis of the wave guide will be employed. Thus waves will herein be designated as transverse magnetic (TM) or transverse electric (TE).

In using sections of cylindrical wave guide to provide a rotatable joint for a wave guide system, it is often and usually necessary to couple energy into and out of the cylindrical sections from and into other types of transmission lines. Thus, for example, in an electrical system that uses a rectangular wave guide as a transmission line, the insertion of a rotatable joint in the transmission line requires that energy of the mode being used in the rectangular wave guide be converted to an axially symmetrical mode upon entering the rotatable joint and then be reconverted to the mode of the rectangular wave guide upon leaving the rotatable joint. However, it is difficult and very often impossible to set up initially in a wave guide a single pure mode of oscillation. Even after choosing the dimensions of the various wave guide sections so as to pro-

vide the most favorable combination for transferring energy with minimum losses, it is usually found that a substantial amount of energy is being lost in standing waves caused by one or more unwanted modes of oscillation. In a rotatable joint, the unwanted mode often takes the form of one that is not axially symmetrical. The presence of such a mode of oscillation results in losses that vary as the rotatable joint is rotated, causing varying attenuation in signal strength that reduces the efficiency of the complete system. Further difficulties are introduced by such an axially non-symmetrical mode in that it results in the rotatable joint being frequency sensitive and of relatively narrow band width, thus requiring careful tuning operations. In my invention I have provided a mode filter for wave guides that filters out a mode of oscillation that is non-symmetrical axially while simultaneously having no effect on an axially symmetrical mode of oscillation.

It is an object of my invention to provide such a filter that will respond to and effect the attenuation of axially non-symmetrical modes of oscillation while simultaneously being non-responsive to an axially symmetrical mode of oscillation.

It is another object of my invention to provide for such a filter a supporting structure that will not attenuate the desired mode of oscillation.

It is a further object of my invention to provide such a filter that will be non-responsive to radially disposed lines of electric force when installed in a cylindrical wave guide.

It is a still further object of my invention to provide such a filter that will be simple to construct, easy to install and adjust, and of light weight.

Other objects and features of my invention will become apparent upon a careful consideration of the following detailed description when taken together with the accompanying drawings, the figures of which illustrate typical embodiments of the invention.

45. In the drawings:

Fig. 1 illustrates a portion of a wave guide transmission line system having a rotatable joint therein;

Fig. 2 is a cross section of a portion of a rotatable joint for a wave guide, broken away at one end, showing a filter in accordance with my invention in place therein;

Fig. 3 is a cross section taken on line III—III of Fig. 2 showing the structure of a filter of my invention; and

Fig. 4 is a cross section of a portion of a rotat-

able joint showing an alternative embodiment of my invention.

In Fig. 1, a transmission line of the rectangular wave guide form 1 is connected to a section of cylindrical wave guide 2, which is part of a rotatable joint. Electrical coupling and anti-friction devices are indicated by the housing 3 which encloses them. The housing 3 is attached to a second section of cylindrical wave guide 4, which is coaxial with the first section 2. The second section 4 is rotatable with respect to the first section 2 about their common axis.

Typical structure of the sort enclosed in the housing 3 is shown in the housing 3' in Fig. 4, and discussed in detail in the hereinabove referred to patent and copending application. The two sections of coaxial line 2' and 4' are coaxially aligned, and abutting but not touching each other at their adjacent faces 5 and 6. The housing 3' is permanently attached to one cylindrical wave guide section 4', and has an annular slot 7 provided therein for the purpose of facilitating electrical coupling between the two sections 2' and 4'. Anti-friction bearings 8 in concentric races 25 and 26 are provided to permit easy rotation of one cylindrical section 2' with respect to the other 4'. The outer race 25 is fixedly held in the housing 3' by the threaded retainer ring 27. The face ring 5' is affixed to the inner race 26 on one side thereof and the threaded ring 15 is affixed to the same race 26 on the opposite side thereof. A second threaded ring 16 is affixed to the other cylindrical wave guide section 2', and is adapted to cooperate rotatably with the first threaded ring 15. Rotation of the cylindrical section 2' and its thereunto affixed ring 16 with respect to the cooperating ring 15 effects axial motion of the cylindrical section 2' with respect to the abutting section 4', while simultaneously preserving constant and undisturbed the spacing between the abutting faces 5 and 6. This spacing is important, similarly to the slot 7 in coupling energy from one cylindrical section 4' to the other 2'. The cylindrical wave guide sections 2 and 4 of Fig. 1 are spaced and supported in a fashion similar to the sections 2' and 4' of Fig. 4.

Returning now to Fig. 1, the second section 4 is connected to a rectangular wave guide 9 of the same sort as the original transmission line 1. The two parts of the rectangular wave guide 1 and 9 are thus movable, one with relation to the other about the axis of the cylindrical wave guide sections 2 and 4 because of the presence of the rotatable joint.

As normally and preferably operated, energy is carried in the rectangular wave guides 1 or 9 in the TE₀₁ mode. Upon entering the cylindrical wave guide 2 from the transmission line 1 this TE₀₁ mode energy is changed to energy in the TM₀₁ mode for cylindrical wave guides, which is an axially symmetrical mode. The TM₀₁ mode is easily excited in the cylindrical section 2 by energy in the TE₀₁ mode emanating from the transmission line 1. Upon leaving the cylindrical section 4 and entering the rectangular section 9, the energy in the TM₀₁ mode is reconverted to energy in the TE₀₁ mode for rectangular wave guides. Electrical energy may pass in either direction through the system of Fig. 1.

As hereinabove explained, a single pure mode of oscillation is not to be expected initially in the cylindrical wave guide sections 2 and 4. Even after all known precautions as to the dimensions of the various wave guide sections and

to matching impedances have been taken, a mode of oscillation that is non-symmetrical about the common axis of the cylindrical sections 2 and 4 will be present. This may be and often is the TE₁₁ mode, and it is undesirable for the reason that it consumes energy that would otherwise pass through the rotating joint in the desired mode, TM₀₁. Energy consumed in the undesired TE₁₁ mode of oscillation represents a corresponding attenuation of the desired signal passing through the rotating joint.

Since the TE₁₁ mode of oscillation is non-symmetrical about the axis of the cylindrical wave guide sections 2 and 4, the energy it consumes will vary as the two sections 2 and 4 of the rotating joint are rotated with respect to each other, thereby causing variable attenuation of the signal sought to be transmitted through the wave guide system of Fig. 1. Where for example the wave guide system of Fig. 1 is being used in a radio echo detection system to carry energy between a transmitter-receiver combination and a rotatable scanning antenna, both the outgoing and the incoming signals will be subject to such variable attenuation, with the result that the information presented by the detection system will be unstable and perhaps useless. Thus it is seen that in a rotating joint like that shown in Fig. 1 the TE₁₁ mode of oscillation in the cylindrical sections 2 and 4 of the joint is undesirable and should be eliminated.

I have found that a ring of conducting material 10 shown particularly in Figs. 2 and 3 mounted transversely in a section of cylindrical wave guide 2, as illustrated in Fig. 3, will be energized by and reflect energy in the TE₁₁ mode of oscillation, but will not be energized by energy in the TM₀₁ mode. The TM₀₁ mode of oscillation will not be affected by the ring 10 since the electric vector for the TM₀₁ mode of oscillation is everywhere perpendicular to the circumference of the ring 10. The electric vector for the TE₁₁ mode is, however, not everywhere perpendicular to the circumference of the ring, and there will consequently be currents induced in the ring 10, and the ring 10 will oscillate at the frequency of the energy exciting the ring 10. I have found further that if the mean circumference of the ring 10 be approximately equal to 1.2 times the free space wave length corresponding to the frequency of the wave being carried in the wave guide 2, the ring 10 will be resonant to that frequency. Such a ring 10 positioned in the wave guide 2 will cause substantially total reflection of oscillations in the TE₁₁ mode in the wave guide 2. A ring 10 of this sort will operate as a filter to inhibit or substantially prevent the propagation of the TE₁₁ mode of oscillation in the wave guide 2 when further positioned as illustrated in Figs. 2 and 4.

In Fig. 2 there is shown a cross section of the lower end of the apparatus illustrated in Fig. 1 comprising parts of the section of rectangular wave guide 1 and the section of cylindrical wave guide 2. In this form of apparatus both the terminating wall 11 and the reflecting filter ring 10 are fixed in position with respect to the junction of the rectangular wave guide 1 and the cylindrical wave guide 2. The metallic ring 10, preferably positioned concentric with the wave guide 2, is mounted upon a hollow cylinder 12 of an insulating material, preferably polystyrene. The cylinder 12 may be mounted in any convenient manner on the wall 11 and in Fig. 2 it is shown fitted about a slight cylindrical projec-

tion 13, the edges of which serve to position the cylinder 12. The cylinder 12 is preferably cemented to the wall 11 and its projection 13. The advantage of the axial type of mount 12 of the reflecting ring 10 shown in Fig. 2 is that the insulating material of the support 12 for the filter ring 10 is arranged in a manner adapted to absorb a minimum of energy from the field of the TM_{01} mode of oscillation in the cylindrical wave guide 2, the electric vector of said field being radial with respect to the cylindrical wave guide 2. It is to be understood that an adjustable support for the ring 10 could be provided, if desired, by a suitable arrangement for moving the cylinder 12 axially with respect to the wave guide 2. The upper end of the rotatable joint of Fig. 1, comprising the companion cylindrical wave guide section 4 and the rectangular wave guide 9 connected thereto, is identical to the end shown in Fig. 2. It is to be understood that the apparatus of Fig. 2 is in itself a complete system for transforming electrical energy from one mode to another, able to function in both directions.

The ring 10 is so positioned with relation to the rectangular wave guide 4 that oscillations in the TE_{11} mode set up at the junction of the wave guides 1 and 2 which are reflected by the ring 10 will cancel the TE_{11} mode oscillations proceeding from said junction away from the ring 10, thereby inhibiting or even preventing the propagation of the TE_{11} mode of oscillation down the wave guide 2. For such action the plane of the filter ring 10 should be approximately an electrical quarter wave length for the TE_{11} mode away from the aforesaid junction, as shown in Fig. 2, or any odd number of quarter wave lengths away from said junction. The line III-III lies in the plane of the ring 10, and the line B-B represents the center line of the rectangular wave guide 4, and hence in effect the mid-point of the junction of the rectangular wave guide 4 and the cylindrical wave guide 2. The distance between these two lines, III-III and B-B should be approximately an electrical quarter wave length but may be any odd number of electrical quarter wave lengths as hereinabove specified. This is in accordance with well known principles of wave transmission.

In a complete rotatable joint, as shown in Fig. 1, the distance between the filter rings 10 in each end of the apparatus is made such as to avoid resonance for the TE_{11} mode of oscillation. Each filter ring 10 should be positioned for cancellation of the TE_{11} mode oscillations proceeding down its cylindrical wave guide section 2 or 4 as hereinabove taught, and the length of the cylindrical wave guide system should be such as to obtain the non-resonance spacing between filter rings 10. Apparatus such as that contained in the housing 3', shown in Fig. 4, comprising threaded collars 15 and 16, will permit one cylindrical wave guide section 2 to be moved axially with respect to the other cylindrical section 4 without varying the spacing between the abutting faces of the two cylindrical sections, as described hereinabove.

Because of the presence of the filter ring 10 and an identical companion ring in the cylindrical wave guide sections 2 and 4, the distance between the closure 11 and the corresponding closure 17 at the other end of the cylindrical wave guide system is no longer sensitive to TE_{11} mode resonances. As a result, the rotating joint is no longer sharply sensitive to frequency changes.

and does not require critical tuning adjustment of the closures 11 and 17. For this reason the terminations 11 and 17 of the cylindrical wave guides 2 and 4 may be permanent in nature. The closure 11 reflects the TM_{01} mode, which is the desired mode, and this closure 11 should be spaced approximately an electrical half-wave length for the TM_{01} mode, or a multiple thereof, from the junction of the rectangular wave guide 4 and the cylindrical wave guide 2. This preferred spacing is indicated in Fig. 2, where a spacing of one-half wave length is shown. With this preferred spacing, the closure 11 will reflect waves in the TM_{01} mode so that they will reinforce similar TM_{01} mode oscillations proceeding down the cylindrical wave guide 2 from the junction of the two wave guides 4 and 2, in accordance with the well known principles of wave transmission. Oscillations in the TE_{11} mode do not reach the closure 11, having been reflected away from the closure 11 by the resonant filter ring 10. Similar spacing of the closure 17 of the other end 4 of the cylindrical wave guide system from the corresponding junction of two wave guides 4 and 9 is provided.

If desired, the filter ring 10 and the closure 11 may either or both be made movable along the longitudinal axis of the cylindrical wave guide system. A modification of the apparatus of Fig. 2 including these features is shown in Fig. 4. A part of the cylindrical wave guide structure of the rotating joint of Fig. 1 is shown including the cylindrical wave guide section 4' and the housing 3'. The closure 17 of Fig. 1 is altered and the cylindrical section 4' is extended in length to provide room for a movable closure 18. The closure 18 may be axially adjusted within the cylindrical wave guide 4 by means of a screw 19 and a hand nut 20. The hand nut 20 is rotatably held against motion along the longitudinal axis of the wave guide 4' by the wall 21, which is not the electrical closure for the cylindrical wave guide 4'. The closure 18 makes electrical contact with the inner surface of the wave guide 4' by means of spring-like metallic fingers 22, separated by slots 23. A resonant filter ring 10', which may be identical to the ring 10 of Fig. 2 is mounted transversely with respect to the wave guide 4' upon an insulating support 24 which is adapted to position the filter ring 10' concentrically within the wave guide 4'. The supporting insulator 24 may conveniently be made of mica or mica-bearing material. The position of the filter ring 10' may be adjusted by sliding the insulating structure 24 axially along the wave guide 4'.

As in the apparatus of Fig. 2, the apparatus of Fig. 4 is preferably adjusted so that the filter ring 10' is spaced from the junction of the cylindrical wave guide 4' and the rectangular wave guide 9 approximately an electrical quarter-wave length for the TE_{11} mode of oscillation. Similarly, the closure 18 is preferably spaced from the same junction a distance equal approximately to an electrical half-wave length for the TM_{01} mode of oscillation. These dimensions are indicated on Fig. 4. As in the structure of Fig. 2, a complete rotating joint of the Fig. 4 embodiment has identical structure at the opposite ends. The same refinements and adjustments that apply to the apparatus of Fig. 2 apply to the apparatus of Fig. 4. Indeed, the latter functions as if it were the former when properly adjusted.

If desired, a rotating joint may have the apparatus of Fig. 4 in one end, as in section 4', and the apparatus of Fig. 2, in the other end, as

section 2 thereof. Further, the fixed closure 11 of Fig. 2 may be used if desired, with the movable ring supporting structure 24, of Fig. 4, or other suitable movable structure.

It is to be understood that electrical energy may pass through a rotating joint having the filter of my invention therein in either direction. The filter rings 10 and 10' will operate to inhibit energy in the TE₁₁ mode from entering as well as leaving a connected rectangular wave guide 10 or 9.

Although I have shown and described only certain specific embodiments of my invention, I am fully aware of the many modifications possible thereof. Therefore this invention is not to 15 be limited except insofar as is necessitated by the prior art and the spirit of the appended claims.

I claim:

1. In a cylindrical wave guide fed at a point in a side thereof by a generator that introduces into said guide electric waves in the TM₀₁ and the TE₁₁ modes, means for attenuating the TE₁₁ mode but not the TM₀₁ mode comprising a metallic annulus positioned within said guide in a plane substantially transverse to the axis thereof, said plane being spaced from said point by a distance substantially equal to one quarter of the length of one of said waves in the TE₁₁ mode.

2. In a cylindrical wave guide system fed at a point in its side by a generator of energy of a certain frequency in the TM₀₁ and the TE₁₁ modes, a metallic annulus having its circumference substantially equal to 1.2 times the free-space wave length of said energy positioned axially within said wave guide in a plane substantially transverse to the axis thereof for resonantly responding to and reflecting waves of said energy in the TE₁₁ mode, said plane being substantially one quarter of a TE₁₁ mode wave length from said point, whereby said reflected waves meet waves of the TE₁₁ mode at said generator in substantially opposing phase to effect mutual cancellation of waves in said TE₁₁ mode.

3. A mode transformer for transferring electromagnetic energy in the TE₀₁ mode in a rectangular wave guide to electromagnetic energy in the TM₀₁ mode in a cylindrical wave guide comprising, a right-angle junction between a rectangular wave guide and a cylindrical wave guide wherein the broad walls of said rectangular wave guide are perpendicular to the longitudinal axis of said cylindrical wave guide whereby oscillations principally in the TM₀₁ mode and incidentally in the TE₁₁ mode are excited in said cylindrical wave guide when said rectangular wave guide is energized in the TE₀₁ mode, and means for selectively attenuating the TE₁₁ mode comprising a conducting end closure for said cylindrical wave guide spaced from the central axis of said rectangular wave guide a distance substantially equal to a half wave length of energy in the TM₀₁ mode, and a conducting annulus positioned coaxially within said cylindrical wave guide and spaced from the central axis of said rectangular wave guide in the direction of said end closure a distance substantially equal to a quarter wave length of energy in the TE₁₁ mode.

4. Apparatus in accordance with claim 3 wherein in said conducting annulus is maintained in position by an insulating annulus surrounding said conducting annulus and contacting the inner surface of said cylindrical wave guide.

5. Apparatus in accordance with claim 3 wherein in the mean circumference of said conducting annulus is substantially 1.2 times the free space

wave length of said energy, and said conducting annulus is positioned by an annulus of insulating material surrounding said conducting annulus and contacting the inner surface of said cylindrical wave guide.

6. A mode transformer for transferring electromagnetic energy in the TE₀₁ mode in a rectangular wave guide to electromagnetic energy in the TM₀₁ mode in a cylindrical wave guide comprising, a right-angle junction between a rectangular wave guide and a cylindrical wave guide wherein the broad walls of said rectangular wave guide are perpendicular to the longitudinal axis of said cylindrical wave guide whereby oscillations principally in the TM₀₁ mode and incidentally in the TE₁₁ mode are excited in said cylindrical wave guide when said rectangular wave guide is energized in the TE₀₁ mode, and means for selectively attenuating energy in the TE₁₁ mode comprising a metallic end plate positioned transversely of said cylindrical wave guide and spaced from the central axis of said rectangular wave guide a distance substantially equal to a half wave length of energy in the TM₀₁ mode, and a resonant ring supported coaxially within said cylindrical wave guide by an insulating cylinder, said cylinder being secured to said end plate and having a length to position said ring from the central axis of said rectangular wave guide a distance in the direction of said end plate substantially equal to a quarter wave length of energy in the TE₁₁ mode.

7. Apparatus in accordance with claim 4 wherein in the mean circumference of said ring is substantially 1.2 times the free space wave length of said energy.

8. A mode transformer for transferring electromagnetic energy in the TE₀₁ mode for rectangular wave guides to electromagnetic energy in an axially symmetrical mode for cylindrical wave guides comprising, a right-angle junction between a rectangular wave guide and a cylindrical wave guide wherein the broad walls of said rectangular wave guide are perpendicular to the longitudinal axis of said cylindrical wave guide whereby oscillations in axially symmetrical and axially unsymmetrical modes are excited in said cylindrical wave guide when said rectangular wave guide is energized in the TE₀₁ mode, and means for selectively attenuating energy in the axially unsymmetrical mode comprising a conducting end closure for said cylindrical wave guide spaced from the central axis of said rectangular wave guide a distance substantially equal to a half wave length of energy in the axially symmetrical mode, and a conducting ring dimensioned to be resonant to said energy and positioned transversely and coaxially of said cylindrical guide and spaced from the central axis of said rectangular wave guide in the direction of said end closure a distance substantially equal to a quarter wave length of energy in said axially unsymmetrical mode.

9. In combination with a right-angle junction between a rectangular wave guide and a cylindrical wave guide wherein the broad walls of said rectangular guide are perpendicular to the longitudinal axis of said cylindrical wave guide, means for improving the transfer of electromagnetic energy in the TE₀₁ mode from said rectangular wave guide to electromagnetic energy in the TM₀₁ mode in said cylindrical guide comprising, a conducting closure for said cylindrical guide spaced from the central axis of said rectangular guide a distance substantially equal to a half wave length of energy in said TM₀₁ mode,

and a conducting ring positioned coaxially within said cylindrical guide, said ring being disposed in a plane transverse to the longitudinal axis of said cylindrical wave guide and spaced from said central axis in the direction of said closure a distance substantially equal to a quarter wave length of energy in the TE₁₁ mode.

10. In a wave guide system, a right-angle junction of a rectangular wave guide and a circular wave guide, said junction being adapted to excite oscillations in said circular guide in the TM₀₁ and TE₁₁ modes when said rectangular guide is energized in the TE₀₁ mode, a conducting end closure adjustably positioned in said circular guide at a distance from the central axis of said rectangular guide substantially equal to an integral number of half wave lengths of energy in the TM₀₁ mode, and a metallic annulus having a mean circumference equal to 1.2 times the free-space wave length of said energy adjustably positioned coaxially within said circular guide in a plane transverse to the longitudinal axis of said circular guide, said plane being spaced from the central axis of said rectangular wave guide in the direction of said end closure a distance substantially equal to an odd number of quarter wave lengths of energy in the TE₁₁ mode, said combination being adapted to attenuate energy in the TE₁₁ mode and to propagate energy in the TM₀₁ mode without attenuation.

11. Apparatus of the class described comprising in combination a right-angle junction of a cylindrical wave guide and a rectangular wave guide for exciting electric waves in said cylindrical guide at said junction in a plurality of modes 35 when said rectangular wave guide is energized,

one of which modes has its electrostatic lines of force disposed in a transverse radial manner within said cylindrical guide, a conducting end closure for said cylindrical wave so spaced from the central axis of said rectangular wave guide that waves reflected from said end closure arrive at said junction substantially in phase with respect to waves emanating from said rectangular wave guide and are mutually reinforced with waves of like modes at said junction, means within said cylindrical wave guide for resonantly responding to and reflecting waves of modes other than said one mode, said reflecting means being so positioned between said end closure and said junction that waves reflected by said means arrive at said junction in substantially opposing phase with respect to waves emanating from said rectangular wave guide and are substantially mutually canceled with waves of like mode at said junction.
